UNITED STATES PATENT OFFICE.

FRED R. BELT, OF CHICAGO, ILLINOIS.

SAFETY-RAZOR.

1,250,775.

Specification of Letters Patent. Patented Dec. 18, 1917.

Application filed January 17, 1916. Serial No. 72,448.

To all whom it may concern:

Be it known that I, FRED R. BELT, a citizen of the United States, residing at Chicago, in the county of Cook and State 5 of Illinois, have invented certain new and useful Improvements in Safety-Razors, of which the following is a specification.

My invention relates to safety razors and it is my object to produce a device of this 10 character which is simple in construction, strong and durable, which will hold the blade firmly and which may be manufactured at a reasonable cost.

The following description when read in 15 connection with the accompanying drawing, illustrating a preferred embodiment of my invention, will be sufficient to make the construction and use of my device clear.

On the drawing

20 Figure 1 represents a side elevation of my improved safety razor, the head thereof being shown in section;

Fig. 2 is a rear elevation showing the lugs for holding the blade in place;

25 Fig. 3 is a plan view showing the complete razor;

Fig. 4 is a perspective view showing the cam, clamping member and guard;

Fig. 5 is a perspective view showing the 30 base;

Fig. 6 is a detail sectional view.

Referring to the drawings, 1 designates a base having upstanding lugs 2 at the rear edge thereof for positioning the blade 3 which, in actual use, is seated on the flat upper face of the base, and end lugs 4 in which the cam member 5 is pivotally mounted. A stem 6, a cam 5', a clamping member 7 and a guard 8 constitute integral parts 35 of the cam member and the handle 6' may be integrally or detachably connected with the stem 6. The base is pivotally connected with the cam member by a pin 9 which passes through an opening 10 in the cam member and engages openings provided therefor in the lugs 4. The ends 11 of the opening 10 are enlarged while the intermediate portion of said opening is made to fit the pivot pin, as shown in Fig. 6.

50 To insert the blade in the razor the base is turned relatively to the cam member by pressing upon the projection 12 until the base lies in a plane substantially parallel

with the handle. This can be easily accomplished by holding the handle in a substantially horizontal position in one hand with the guard directed upward and then pressing downward upon the projection 12 until the base is forced over the high point of the cam whereupon it will swing freely 55 into a substantially horizontal position. The blade can then be inserted in the space between the cam and the base and pushed back until its rear edge engages the lugs 2 after which the base, carrying the blade, is 60 swung upward, being forced over the high point of the cam, which thereupon locks the blade and base in the normal position for use, as shown in Fig. 1. In this position the blade is clamped between the clamping 65 member 7 and the forward edge of the base and also between the cam 5' and the opposite portion of the base so that no vibration of the blade can occur.

To remove the blade from the razor the 70 operation is precisely the same as for inserting the blade but it will be understood that instead of holding the cam member rigid and swinging the base, the base may be held rigid and the cam member swung, although 75 I believe the former method will be found more convenient.

I prefer to make the pivot opening 10 with enlarged ends 11 to permit a freedom of movement and more or less of a bending 80 movement, as may be required, of the pivot pin therein. This enables me to provide a comparatively strong cam action since the enlarged ends 11 of the pivot opening permit the pivot pin to yield therein as may be required when the base carrying the blade is 85 forced over the high point of the cam. I am thereby enabled to provide a secure and rigid lock with the cam which will not become accidentally loosened since the base 90 carrying the blade must be swung over the high point of the cam with a decided snap.

95 My improved razor comprises a minimum number of parts which are assembled in a convenient manner for use and which enables the blade to be easily inserted and removed as required. The blade is clamped in rigid position so that it will be entirely free from vibration in actual use and is securely locked against accidental displacement.

100 105 The yielding pivotal connection of the

base and cam member is important not only for the reasons hereinbefore referred to but to accommodate blades which vary in thickness and also blades of different thickness.

5. I claim:

1. A safety razor comprising a base having a seat thereon adapted to receive a blade, a cam member pivotally engaged with said base to coöperate therewith and secure the blade in place therebetween, and a guard integral with said cam member engaging and projecting beyond said blade.

15. 2. A safety razor comprising a base having a seat thereon adapted to receive a blade, a cam member pivotally engaged with said base to coöperate therewith and secure the blade in place therebetween, and a clamping member and guard integral with said cam member engaging and projecting beyond 20 said blade.

25. 3. A safety razor comprising a base having a seat thereon adapted to receive a blade, and a cam member pivotally engaged with said base to coöperate therewith and secure the blade in place therebetween and having integral therewith a guard projecting beyond the blade and base, a clamping member behind the guard to engage and support the blade, and a cam behind the clamping 30 member to engage the blade.

35. 4. A safety razor comprising a base having a seat thereon adapted to receive a blade, and a cam member pivotally engaged with said base to coöperate therewith and secure the blade in place therebetween and having integral therewith a guard projecting beyond the blade and base, a clamping member behind the guard to engage and support the blade, a cam behind the clamp- 40 ing member to engage the blade, and a stem projecting above the cam to receive a handle.

45. 5. A safety razor comprising a base having a seat thereon adapted to receive a blade and a cam member yieldingly pivoted on said base and comprising an integral cam coextensive in length with and adapted to engage the blade throughout its length to secure the same in place on said seat.

50. 6. A safety razor comprising a base having a seat thereon adapted to receive a blade, and a cam member pivotally engaged with said base to coöperate therewith and secure the blade in place, said cam member having integral therewith a guard engaging and 55 projecting beyond said blade, a cam and a clamping member intermediate of the guard and cam.

60. 7. A safety razor comprising a base having a seat thereon adapted to receive a blade, a cam member pivotally mounted on said base to engage with and secure said plate in place and provided with a longitudinal opening, the pivotal connection consisting of a pin extending through said opening 65 and engaged at its ends with said base, said

opening being enlarged adjacent its ends whereby said pin is free between its end engagement with the base and its central engagement with the cam member.

8. A safety razor comprising a base hav- 70 ing a seat thereon adapted to receive a blade, a cam member having an opening there- through enlarged at its ends, and a pivot pin arranged in said opening and engaged with the base to pivotally connect the cam 75 member with the seat.

9. A safety razor comprising a base hav- 75 ing a seat thereon adapted to receive a blade, and upstanding lugs at the ends of said seat, a cam member arranged between said lugs 80 and adapted to coöperate with said seat to clamp a blade therebetween, said cam member having a bore extending entirely there- through and enlarged at its ends, and a pivot pin arranged in said bore and engaged 85 with said lugs, said pivot pin fitting loosely in the enlarged ends of the bore and snugly in that portion of the bore intermediate of the enlarged ends.

10. A safety razor comprising a base hav- 90 ing a seat thereon adapted to receive a blade, a cam member yieldingly pivoted on said base and comprising an integral cam coextensive in length with and adapted to engage the blade throughout its length to se- 95 cure the same in place on said seat, and a guard integral with said cam member.

11. A safety razor comprising a base hav- 100 ing a seat thereon adapted to receive a blade, a cam member yieldingly pivoted on said base and comprising an integral cam to engage and secure the blade in place on said seat, and a guard integral with said cam member.

12. A safety razor comprising a base hav- 105 ing a seat thereon adapted to receive a blade, and a cam member pivotally mounted on said base and comprising an integral cam coextensive in length with and adapted to engage and secure the blade in place throughout its length, the pivotal connec- 110 tion consisting of a pin engaged at its ends with said base and centrally with said cam member and being free between its end engagement with said base and its central engagement with said cam member.

13. A safety razor comprising a base hav- 115 ing a seat thereon adapted to receive a blade, a cam member pivotally mounted on said base and comprising an integral cam coextensive in length with and adapted to engage and secure the blade in place throughout its length, the pivotal connection con- 120 sisting of a pin engaged at its ends with said base and centrally with said cam member and being free between its end engagement with said base and its central engagement with said cam member, and a guard integral 125 with said cam member.

14. A safety razor comprising a base hav- 130

ing a seat thereon adapted to receive a blade, and a cam member pivotally engaged with said base and comprising an integral cam coextensive in length with and adapted to engage said blade throughout its length to secure the blade in place, an integral guard engaging and projecting beyond the blade,

and a clamping member intermediate the guard and cam.
